UNITED STATES PATENT OFFICE.

HARRY G. DALZELL, OF CHICAGO, ILLINOIS, ASSIGNOR TO FOSTORIA GLASS COMPANY, OF MOUNDSVILLE, WEST VIRGINIA, A CORPORATION OF WEST VIRGINIA.

DESIGN FOR A COMBINED PUFF BOWL AND PERFUME BOTTLE.

Application filed January 10, 1923. Serial No. 4,857. Term of patent 14 years.

To all whom it may concern:

Be it known that I, HARRY G. DALZELL, a citizen of the United States of America, and resident of Chicago, county of Cook, and State of Illinois, have invented a new, original, and ornamental Design for a Combined Puff Bowl and Perfume Bottle, of which the following is a specification, reference being had to the accompanying drawings, in which the figure is a side elevation of a combined puff bowl and perfume bottle, showing my new design.

I claim:

The ornamental design for a combined puff bowl and perfume bottle as shown.

HARRY G. DALZELL.
